DESCRIPTION

FIG. 1 is perspective view of a rack and label showing our new and ornamental design;

FIG. 2 is a front elevation view thereof;

FIG. 3 is a back elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

The broken lines illustrate portions of the rack and label that form no part of the claimed design. The portions of the rack and label shown in FIG. 7 in dotted line cross hatching show portions of the label covering the rack and form no part of the claimed design.
